(57) CLAIM

The ornamental design for a pendant, as shown and described.

DESCRIPTION

FIG. 1 is a front view of a pendant, showing my new design.

FIG. 2 is a rear view of FIG. 1.

FIG. 3 is a top view of FIG. 1.

FIG. 4 is a bottom view of FIG. 1.

FIG. 5 is a right side view of FIG. 1.

FIG. 6 is a left side view of FIG. 1; and,

FIG. 7 is a perspective view of FIG. 1.

The dotted lines show environment only and do not form a part of the claimed design.
